UNITED STATES PATENT OFFICE.

FREDERICK A. SALAMAN, OF NEW YORK, N. Y., ASSIGNOR OF ONE-HALF
TO FRANK HAHN, OF NEW YORK, N. Y.

SHOE SOLE AND HEEL.

SPECIFICATION forming part of Letters Patent No. 738,735, dated September 8, 1903.

Application filed May 4, 1903. Serial No. 155,529. (No model.)

To all whom it may concern:

Be it known that I, FREDERICK A. SALAMAN, a citizen of the United States, residing at New York, in the county of New York, State of New York, have invented certain new and useful Improvements in Shoe Soles and Heels, of which the following is a description, reference being had to the accompanying drawings, and to the figures of reference marked thereon.

10 My invention relates to soles and heels for shoes, and is intended to provide a simple, strong, durable, and inexpensive construction adapted for use as a sole or heel capable of being readily secured in place by any one 15 without the necessity for special skill or experience in shoemaking.

With this purpose in view my invention consists in the construction described herein-after and particularly pointed out in the 20 claims.

Referring to the drawings, Figure 1 is a plan view of the invention as applied to a shoe-sole. Fig. 2 is a cross-sectional view on line *a a* of Fig. 1. Fig. 3 is a cross-sectional 25 view on line *b b* of Fig. 1. Fig. 4 shows the invention applied to a heel of the rotary type. Fig. 5 is a cross-sectional view on line *c c* of Fig. 4, and Figs. 6 and 7 are respectively a plan and cross-sectional view showing my invention applied to a heel of ordinary form.

In the drawings, 1 represents a metallic plate of malleable metal capable of being curved to the shape proper for a shoe-sole and of sufficient stiffness to retain the shape 35 given to it. To this plate strips or pieces 2 of sole-leather are secured by rivets 3, the strips or pieces being preferably recessed sufficiently to permit the upper surface of the plate 1 to be flush with the surface of the portion of the strips or pieces which extends beyond the plate.

The strips or pieces 2 may be of any convenient form and may consist of scraps of sole-leather, which would otherwise be of no practical value. As shown, these strips are of sufficient length to extend across the entire width of the sole; but they may be of less length, if found desirable.

The construction as shown in Figs. 1 to 3, 45 inclusive, and Figs. 6 and 7 is intended to be sold to be applied as a sole-tap or heel-lift by

the purchaser, and for convenience in securing it in position it is provided with screw-holes 4, drilled through the leather facing and the metal plate 1. The plate 1 is made 55 sufficiently narrow to come within the lines of the least broad shoes of the length to which the sole or heel lift is applicable.

After the sole-tap is secured to the shoe by screws through the holes 4 the outer edges of 60 the strips or pieces 2 may be trimmed to the size desired. The plate being embedded in the leather, the portions of the leather outside the lines of the plate will make a tight joint with the sole of the shoe to which the 65 sole-tap is applied.

In the construction shown in Figs. 4 and 5 the plate 1 has secured to it the strips or pieces 2, the plate being, as in the construction shown in Figs. 1 to 3 and 6 and 7, embodied in the leather. I have shown the invention in Figs. 4 and 5 as applied to a rotary heel, having a central recess formed through the leather strips or pieces 2, in which is received the head of a screw 5, which bears 75 against the plate 1, in which is formed an opening 6, through which the screw passes into the main portions of the heel. The main portion of the heel is preferably provided with a metal plate 7, against which 80 the plate 1 lies. To this plate 7 is preferably secured on the forward edge of the heel a strip 8 of leather cut out to receive the periphery of the rotary heel. The head of the screw 5 is flush with the outer surface of the 85 strips or pieces 2 and is preferably provided with a plurality of radial grooves 9 to receive a screw-driver or other tool, the angular portions 10 between these grooves serving to protect the wearer of the shoe against slipping. 90

The plate is preferably provided with projection 11, formed by perforating it with a pointed punch, so as to leave rough edges or burs, which are embedded in the strips or pieces 2. The metallic plate 1, as above described, being curved or dished to the proper form to fit the foot and being sufficiently stiff to preserve this form when in use, serves to bring the sole of the shoe to which it is applied to its proper shape without the necessity for relasting and prevents the shoe-sole from getting out of shape in use. By 95 100

embedding the plate in the strips or pieces of leather they are held firmly in place while they are riveted to the plate and prevent possibility of movement of the strips even though the rivets should become loosened.

5 The wearing-surface being made up of separate strips or pieces of leather, a firmer hold is afforded than is afforded by a sole or heel of a single piece of leather, and as a further 10 means of thus avoiding danger of slipping the contiguous edges of the strips or pieces 2 may be slightly beveled or rounded.

When any portion of the sole becomes worn 15 out, the worn strip may be readily removed and a new strip substituted, so that the entire sole need not be discarded because one portion of it is worn.

Having thus described my invention, what I claim, and desire to secure by Letters Patent, is—

1. In a construction adapted for use as a sole or heel for shoes, a metallic plate shaped to fit the tread-surface of a shoe and strips or pieces of leather secured to the metallic 25 plate, the plate being embedded in the leather strips or pieces, substantially as described.

2. In a construction adapted for use as a sole or heel for shoes, a metallic plate of less

area than the tread portion of the shoe, strips or pieces of leather secured to the metallic 30 plate and extending beyond the lines of the metallic plate, the metallic plate being embedded in the leather strips or pieces so that its surface is flush with the surface of the portions of the leather strips or pieces beyond the lines of the metallic plate; substantially as described.

3. In a construction adapted for use as a sole or heel for shoes, a metallic plate of less area than the tread portion of the shoe strips 40 or pieces of leather secured to the metallic plate and extending beyond the lines of the metallic plate, the metallic plate being embedded in the leather strips or pieces so that its surface is flush with the surface of the 45 portions of the leather strips or pieces beyond the lines of the metallic plate and means for detachably securing the plate to the shoe; substantially as described.

In testimony whereof I affix my signature 50 in presence of two witnesses.

FRED. A. SALAMAN.
